DISPENSING TUBE FOR FOOD OR THE LIKE

Devorah Buxbaum, 123 W. 11th St., New York, N.Y.

Filed Nov. 2, 1964, Ser. No. 82,430

Term of patent 14 years

(Cl. D58—17)

FIG. 3

FIG. 4

FIG. 5

FIG. 1 is a perspective view of a dispensing tube for food or the like showing my new design;

FIG. 2 is an exploded perspective view thereof;

FIG. 3 is a side elevational view thereof;

FIG. 4 is a plan view thereof; and

FIG. 5 is a bottom view thereof.

The dominant features of my invention reside in the portions shown in full lines.

I claim:

The ornamental design for a dispensing tube for food or the like, substantially as shown and described.
